UNITED STATES PATENT OFFICE.

TRUMAN J. PURDY, OF SUNBURY, PENNSYLVANIA.

VOTING BOOTH.

1,426,101.

Specification of Letters Patent. Patented Aug. 15, 1922.

Application filed January 20, 1921. Serial No. 438,719.

To all whom it may concern:

Be it known that I, TRUMAN J. PURDY, a citizen of the United States, residing at Sunbury, in the county of Northumberland and State of Pennsylvania, have invented certain new and useful Improvements in Voting Booths, of which the following is a specification.

This invention relates to voting booths composed of a series of interlocking foldable sections, and more particularly the invention relates to improved means for interlocking the back sections of adjacent booths.

In the accompanying drawing,

Fig. 1 is a perspective view, partly broken away, of two connected booths; and,

Fig. 2 is a top plan view of the same.

Referring to the drawing, *a*, *b*, and *c* indicate the back, a side wall and the spacing member, respectively, of a sectional unit in a system of booths, and *a'*, *b'*, and *c'* indicate similar members in an adjacent section. The back *a* of the unit represented by the parts *a*, *b*, and *c* comprises a rectangular frame composed of parallel uprights 1 and 2, connected by upper and lower cross-bars 3 and 4, the latter having their end portions projecting beyond the uprights 1 and 2. As shown, the end 3^a of the upper cross bar has

on its front face a notch, 3^b and the end portion 3^c has on its rear face a similar notch 3^d. The end portions of the lower cross bar 4 are notched in the same manner as the end portions of the upper cross bar. The part *b*, which forms the side wall for the booth, or a partition between adjacent booths, comprises a suitable frame which is connected by hinges 5 to the upright 1 of the back section, and when the wall or partition *b* is swung into its unfolded position, shown in the drawing, at right angles to the back section, it stands edgewise in front of the ends 3^a of the cross bars 3 and 4. The parts *a* and *b* are faced with suitable light board or wood veneer *j*, and the spacing member *c*, which also constitutes a writing table, is hinged to the facing on the part *b* and when unfolded its free end rests upon a cross bar 6 on the wall or partition *b'* of the adjacent section, each unit being provided with a cross bar 6 to serve as a support for the spacing member of another section.

When the sections are folded, the spacing member *c* folds upward on the partition *b*, and the latter folds inward against the backpiece *a*. In assembling the units, the

back portions are brought together edge to edge with the hooked or notched ends 3^a and 3^c, 4^a and 4^c of their cross bars overlapped and interlocked, as shown in the drawing, and when the partition *b'* is swung to its unfolded position, as shown in the drawing, the rear edge of this partition overlies the ends 3^c and 4^c of the bars of the adjacent unit and thereby the backs of the booths are locked together. As the units are alike, any number of booths may be connected in this simple manner and may be disconnected when the partitions are folded.

The end wall *d* of the series of booths comprises a rectangular frame faced with veneering or board *j* and having upper and lower cross bars 7 and 8, respectively, which bars are extended beyond the rear upright 7^a of the frame and provided with notches 7^b and 8^b, in their upper sides, which interlock with notches in the lower sides of the extended ends of the cross bars of the frame *a'*. It will be evident that the structure described provides a simple and inexpensive interlocking connection between the backs of the booths which permits the parts to be quickly assembled or taken apart.

What I claim is:

1. In a sectional system of voting booths composed of similar units, a unit comprising a back frame having laterally projecting portions having notches in their rear faces at the one end of the same and notches in the forward faces at the other end of the same adapted to interlock with similar portions on adjacent sections, and a partition hinged to one side of the back frame and having its rear edge adapted to engage the projecting portions of an adjacent section when the partition is in unfolded position.

2. In a sectional system of voting booths composed of similar units, a unit comprising a back frame having cross bars projecting beyond the lateral edges of the frame and adapted to overlap and interlock with the projecting ends of cross bars on adjacent frames, and a partition hinged to the back frame and adapted to stand edgewise in front of the projecting ends of the bars at one edge of the frame when the partition is in unfolded position the edge of the partition of one unit engages the projecting ends of the bars of the adjacent unit to hold the two units interlocked together.

3. In a sectional system of voting booths composed of similar units, a unit comprising

a back frame having cross bars the ends of which project beyond the lateral edges of the frame, the end portions of the bars at one edge of the frame having notches in their rear faces and the end portions of the bars at the opposite edge having notches in their forward faces, and a partition attached to the back frame and having its rear edge extending in front of the latter end portions of the bar when the partition is in

unfolded position the edge of the partition of one unit engaging the projecting ends of the bars of the adjacent unit to hold the two units interlocked together.

In testimony whereof I affix my signature 15
in the presence of two witnesses.

TRUMAN J. PURDY.
